UNITED STATES PATENT OFFICE.

HAROLD O. BIGNEY, OF ATTLEBORO, MASSACHUSETTS, ASSIGNOR TO SIDNEY O. BIGNEY, OF ATTLEBORO, MASSACHUSETTS.

DESIGN FOR A CIGARETTE-CASE.

41,858.

Specification for Design.

Patented Oct. 24, 1911.

Application filed July 19, 1911. Serial No. 639,444. Term of patent 7 years.

To all whom it may concern:

Be it known that I, HAROLD O. BIGNEY, a citizen of the United States, residing at Attleboro, in the county of Bristol and State of Massachusetts, have invented a certain new, original, and ornamental Design for a Cigarette-Case, of which the following is a specification.

In the accompanying drawings which form a part of this specification Figures 1, 2, and 3 are respectively front, rear, and plan elevations of a cigarette case embodying my new design.

I claim,

The ornamental design for a cigarette case, as shown.

HAROLD O. BIGNEY.

Witnesses:

HORATIO E. BELLOW,
GEORGE H. McLAUGHLIN.
